ATTORNEYS

UNITED STATES PATENT OFFICE.

JOSEPH E. HAGSTROM, OF CHICAGO, ILLINOIS.

VALVELESS AIR HAMMER.

Application filed February 2, 1920. Serial No. 355,807.

To all whom it may concern:

Be it known that I, JOSEPH E. HAGSTROM, a subject of the King of Sweden, residing at Chicago, in the county of Cook and State 6 of Illinois, have invented certain new and useful Improvements in Valveless Air Hammers, of which the following is a specification.

The invention has for its general object 10 the provision of an air hammer characterized by simplicity of parts and efficiency in operation, the peculiar construction of which results in economy of manufacture, ready accessibility for cleaning or the replacement of parts, freedom from necessity 15 of repair or adjustment, and efficient operation under all conditions of use.

A particular object of the invention is the provision of such an implement wherein the 20 construction is such as to utilize effectively the kinetic power of the actuating fluid in addition to the actual pressure thereof, for the purpose of doing work.

Another particular object is the provision 25 of such an implement wherein the friction of moving parts is materially eliminated and reduced.

A still further object is the provision 30 of an implement having such a construction as will occasion the exhaust of a minimum amount of pressure fluid at each stroke.

Another object is the provision of a pneumatic hammer and similar implement wherein the construction is such as to effectively 35 protect the device from the pounding of moving parts during its operation.

Other and further objects will be obvious 40 from the following description and the drawings forming a part of this specification, or indicated in the appended claims.

A description of the construction and operation of the improved hammer follows. It is to be understood, however, that the precise embodiment herein disclosed is to 45 be considered as illustrative of rather than as unnecessarily limiting the scope of the present invention.

In the drawings:

Fig. 1 is a side elevation of the air hammer, the barrel of which is partially broken away to show the interior parts at the end of the working stroke,

Fig. 2 is a top view of the same,

Fig. 3 is a central longitudinal section 55 illustrating the parts at approximately the end of the return stroke,

Fig. 4 is a fragmentary view, partially in section, showing tool inserted in end of hammer,

Fig. 5 is a view similar to Fig. 4, but 60 showing means for adapting the old type of tool to this hammer.

Referring now in detail to the accompanying drawings, for purposes of exemplification, the numeral 10 designates generally 65 the frame member which is of an irregular shape and functions both as a handle and as a frame to which the body or barrel member 11 is attached. Said barrel is held in position by a circular flange 12 extending 70 from the frame 10. At one side the flange has cut in its periphery a narrow slot 13, and projecting outwardly on each side of said slot is a lug 14 perforated and threaded 75 to receive a screw 15. By means of this screw the lugs 14 are drawn together causing the flange 12 to constrictively grip one end of the barrel 11.

A rectangular key plug 16 having a semi-circular groove 17 cut in its outer surface 80 to receive the shank of the screw 15 fits snugly in the slot 13. The inner surface of said plug contacts with the barrel 11 and a protruding stud 18 seats in a hole 19 of the barrel, thus securing said barrel to the 85 frame against both angular and longitudinal movement as long as the screw 15 is in its operative position.

At the other end of the barrel 11 is a reducing bushing 20 which is either formed 90 integral with or secured rigidly within the said barrel. This bushing receives the shank of a removable tool 21, or if it so happens that the tool shank is of small diameter, an auxiliary bushing 22 may readily be 95 brought into use. Another function of the bushing 20 is to form an annular groove 23 within which seats one end of the operating coil spring 24.

A handle 25 is formed in the frame 10 and 100 has cut in its upper portion a slot 26. This slot is designed to receive the finger operated levers 27 and 28 which are pivotably mounted on the pins 29 and 30 respectively. These pivot pins extend into the opposing walls of the slot 26, and the ends of

the pins are flush with the sides of the handle 25. Situated in the frame 10 is a vertical bore 31 extending inwardly from the top of the head member and from the inner end of the bore 31, a much smaller bore 32 which serves as an oil drain, continues to the opposite side of said frame.

A cylindrical slide valve plug 33 fits snugly in the bore 31 and has intermediate its length an annular groove 34. Positioned by a lug 35 at the bottom of the valve plug 33 is a compression spring 36 which tends to expel the valve plug and hold its outer end in contact with the pivoted arm 28 which, when the thumb piece 37 of the lever 27 is depressed, forces the valve plug 33 inwardly against the compression of spring 36, thus causing the groove 34 to register in horizontal alinement with an air supply passage 38 through the frame. This air passage 38 terminates in an enlarged portion 39 which is suitably tapped to receive a threaded air hose connection.

Concentric with the flange 12 and the horizontal portion of the passage 38 is a cylindrical boss 40 of the frame 10. This projection has a threaded horizontal hole 41 in its center, and is both alined with and connected to the heretofore-mentioned passage 38.

A centrally located guide rod or core 42 which contains a passage 43 through approximately half of its length, has a threaded connection at one end in recess 41. A lock nut 42^a, similarly threaded fixedly secures the rod 42 in the frame and prevents accidental displacement. The passage 43 is thus permanently alined with and forms a continuation of the passage 38 through the frame of the air hammer.

At a point corresponding to the termination of the passage 43 on the guide rod 42 is an egg-shaped enlargement 44, all vertical transverse sections of which are circular. This enlargement may be either constructed integral with the shaft 42 or may be rigidly positioned therewith. A plurality of radially disposed ports 45 lead obliquely from the passage 43 to the forward face of the enlargement 44. The remainder of the rod 42 from the enlargement 44 to its forward end 46, which seats loosely in a recess in the end of the tool 21 and which recess in turn acts as a brace for said rod, is preferably solid and functions as a guide for the hammer piston 47 which fits snugly and is longitudinally movable thereon. The piston member 47 is of cylindrical cup shape, its outer diameter being slightly less than that of the inside of the barrel 11 so as to be out of contact therewith. At its forward end the piston diameter is reduced as at 48 to form a seat for one end of the heretofore mentioned coil spring 24.

65 The inside of the marginal portion of the

piston 47 is reamed out at a constant diameter for a portion of its length, as at 49, in order to telescope the corresponding cylindrical portion 50 of the enlargement of core 42. At a point adjacent the exterior openings of the radial ports 45 the interior recess of the piston member 47 tapers down to a point approximately in lateral alinement with the annular abutment 48^a on the exterior of the hammer member, thus presenting a cuneiform recess to receive the forward portion of the reaction member 44 but of greater depth and more gradual slope. From the point 52 to the end of the interior bore of the piston member this portion acts as an air tight sleeve in sliding relation to the solid cylindrical portion 53 of the guide rod or core 42.

An exhaust vent 54 is formed between the barrel and frame members by the slot 13 while two additional exhaust vents 55 may be provided as shown.

The operation of this pneumatic hammer is as follows:

A fluid, preferably air, is admitted under pressure by means of some approved hose connection to the passage 38 by way of the enlarged opening 39. Inasmuch as the annular groove 34 in the cylindrical valve plug is normally not in alinement with the horizontal passage 38, the compressed air in said passage is effectually shut off from the operating mechanism of the hammer. In order to operate the pneumatic hammer the thumb piece 37 is pressed, and the cylinder 33 is in consequence forced downwards. The annular groove 34 coming into alinement with the passage 38 permits the compressed air in said passage to pass into the duct 43 of the core 42. The compressed air in said duct is led through the radial ports 45 and impinges against the cuneiform surface 51 of the piston, as a result of which said piston is driven forcibly forward, compressing the spring 24, until the forward end 56 of the piston strikes the end 57 of the tool 21. When this point is reached the piston has traveled sufficiently forward for the rim 58 to clear the portion 50 of the enlargement and to uncover the ports 45, thus allowing the compressed air to escape into the barrel 11 and to exhaust through the heretofore mentioned vents 54 and 55. The force of the compressed air now being removed from behind the piston, the stressed coil spring 24 forces the piston back into its normal position, and the reciprocating action of the hammer member is rapidly and continuously repeated so long as the valve plug is held in open position by the thumb piece.

From the foregoing description, it will be observed that my improved construction employs but a single moving part, viz., the striker 47, which delivers its work blow directly against the tool, and which, on its

return stroke, is stopped by the pressure fluid before it has opportunity of striking a blow on any abutting portion of the device. The direct impingement of the actuating fluid from the ports 45 upon the surface of the movable striker, and particularly upon said surface at an angle with respect to the direction of travel of the striker, utilizes effectively the kinetic power of the pressure fluid. The diverging relationship of the wall 51 relative to the tapering wall of the reaction member forms an expansion nozzle through which the pressure fluid is injected, whereby its velocity is increased. The relationship of the wall 51 to the sides of the guide 53 forms a contracting chamber with the wall of the striker in position to receive the injected fluid. By this arrangement the effectiveness of the pressure fluid for propelling the striker is augmented. By virtue of this construction, furthermore, the increase in cubic capacity of the pressure chamber by movement of the striker is relatively small, so that a high compression is effected and only a small amount of pressure fluid exhausted at each stroke. The construction is also effective to materially reduce the friction area between the moving parts, as the striker is carried on the small diameter guide 53 and has but small surface bearing on the cylindrical portion 50, and has no friction engagement with the barrel 11.

It will be understood that any pressure fluid may be used as a motive force and that the term "air" is used in a general sense; also that other terms used in connection with the particular embodiment of the invention shown and described are to be construed liberally.

I claim:

1. In an air hammer, the combination of a barrel providing a tool mounting in its forward end, a rod fixed axially in the barrel and having thereon an enlargement with a forwardly coned face, the rod having an air passage therethrough with ports opening to its face, a cup-like piston guided within the barrel in advance of the enlargement, a spring forcing the piston rearwardly and means to control the air supply to the ports.

2. In an air hammer, the combination of a barrel providing a tool mounting in its forward end, a rod fixed axially in the barrel and having thereon an enlargement with a forwardly coned face, the rod having an air passage therethrough with ports opening obliquely to its face, a cup-like piston guided within the barrel and having a rearwardly opening recess to receive the enlargement and to conform approximately in shape to the face thereof, a spring forcing the piston rearwardly and means to control the air supply to the ports.

3. In an air hammer, the combination of

a barrel providing a tool mounting in its forward end, a rod fixed axially in the barrel and having thereon an enlargement with a forwardly coned face intermediate its length, the rod having an air passage therethrough with forwardly directed ports opening at the enlargement thereof obliquely to its face, a cup-like piston guided within the barrel on the rod in advance of the enlargement, a spring forcing the piston rearwardly and means to control the air supply to the ports.

4. In an air hammer, the combination of a barrel providing a tool mounting in its forward end, a rod fixed axially in the barrel and having thereon an enlargement with a forwardly coned face intermediate its length, the rod having an air passage therethrough with forwardly directed ports opening at the enlargement thereof obliquely to its face, a cup-like piston guided within the barrel on the rod in advance of the enlargement, the piston having a rearwardly opening recess corresponding in shape approximately to the coned face of the enlargement but of greater depth and with the inner diameter of its rim corresponding to the outer diameter of the enlargement at the rear of the ports and extending beyond said ports, a spring forcing the piston rearwardly and means to control the air supply to the ports whereby in the rearmost position of the piston the air will be directed into the recess in advance of the enlargement to propel the piston forwardly and uncover the ports whereupon the air will be free to exhaust until the spring returns the piston and again closes off the the escape around the enlargement.

5. In an air hammer, the combination of a frame providing a handle, a boss, and a split flange about the boss, said frame having a valve controlled air passage through the boss, a barrel clamped within the split flange about the boss and providing at its forward end a tool mounting, a rod having connection with the boss and disposed axially within the barrel, the rod having an air passage therethrough with ports opening to its surface, a piston guided within the barrel on the rod in advance of the ports, and a spring forcing the piston rearwardly.

6. In an air hammer, the combination of a frame, providing a handle, a boss, and a split flange about the boss, said frame having a valve controlled air passage through the boss, a barrel disposed within the split flange about the boss, a set screw bridging the split in the flange to clamp the same upon the barrel, a key engaged by the screw and having a stud engaging the barrel to form an interlocking engagement between the barrel and flange, said barrel providing at its forward end a tool mounting, a member having connection with the boss and disposed axially within the barrel, said member having

an air passage therethrough with ports opening to its surface, a piston guided within the barrel on said member in advance of the ports, and a spring forcing the piston rearwardly.

7. In an air hammer, the combination of a frame providing a handle, a boss, a split flange about the boss, said frame having a valve controlled air passage through the 10 boss, a barrel clamped within the flange in spaced relation to the boss and providing at its forward end a tool mounting, a rod threaded into the boss and extending axially of the barrel, said rod having intermediate 15 its length an enlargement presenting a forwardly coned face and provided with an interior air passage with forwardly directed ports opening to the coned face of the enlargement, a cup-like piston guided upon the 20 rod between the enlargement and the tool mounting, said piston having a rearwardly opening conical recess of slightly greater depth than the coned enlargement and adapted to receive the same, the rim of the 25 recess extending rearwardly beyond the ports and having an interior diameter corresponding to the exterior diameter of the enlargement at the rear of the ports, a compression spring disposed in advance of the 30 piston whereby in the rearmost position of the piston the air will be directed through the ports into the recess in advance of the enlargement to propel the piston forwardly and uncover the ports by the rim whereupon 35 the air will be free to exhaust until the spring returns the piston and again closes off the escape around the enlargement.

8. A pneumatic engine and the like, comprising a frame affording free mounting for 40 a tool, an axial guide member, a striker slidably mounted on the guide member for engagement with a tool in the mounting, yielding pressure means for retracting the striker from the mounting, said striker being formed with a tapered axial chamber, a member in alignment with the guide forming a closure for said chamber when the striker is in retracted position, said member being provided with channels for directing 45 pressure fluid against the wall of said chamber when it is closed, and means for controlling supply of pressure fluid to said channels.

9. In a device of the class described, the 55 combination of a frame affording a mounting for a tool, a guide supported on the frame for alignment with a tool supported on said mounting; a striker mounted on said guide for reciprocating movement toward 60 and from such tool, said striker being formed with an internal cavity having a lateral wall converging toward the guide, a member supported on the frame in alignment with the guide for insertion into said 65 cavity and effective to close the same dur-

ing a portion of the travel of the striker, said member being provided with a duct arranged to direct fluid against the interior wall of the striker, and means for controlling supply of pressure fluid to said duct, 70 to propel the striker toward the tool mounting.

10. In a device of the class described, the combination of a frame provided with a tool mounting, a striker slidable on the frame toward and from the tool mounting, said striker having a rearwardly opening axial cavity with walls converging toward the tool mounting, a member mounted on the frame for reception into said cavity and provided with a duct arranged to direct pressure fluid against the wall thereof, a member arranged to close the cavity during a portion of the travel of the striker, said striker being movable to clear said last mentioned member, yielding means for moving the striker from the tool mounting, and means for controlling supply of pressure fluid to said duct. 75 80 85

11. In a device of the class described, the combination of a frame supporting a tool mounting, a striker slidably mounted on said frame for movement toward and from the tool mounting, said striker being provided with an axial cavity of decreasing area toward the tool mounting, a member mounted on the frame and having tapering walls adapted to be received in to said cavity, said member being provided with a duct arranged to direct fluid against the wall of the cavity, means being provided for effecting movement of the striker from the tool mounting, and means for controlling supply of pressure fluid to said duct. 90 95 100

12. In a device of the class described, the combination of a frame provided with a tool mounting, a member mounted on the frame and having a tapering portion directed toward the tool mounting, a striker mounted for movement from said member to the tool mounting and provided with a tapering cavity arranged to receive said member, yielding means for moving the striker onto said member, said member being provided with a duct arranged to inject fluid between its tapering portion and the striker, and means for controlling the supply of pressure fluid to said duct. 105 110 115

13. In a device of the class described, the combination of a frame, a tool mounting supported thereon, a reaction member supported on the frame in alignment with the tool mounting, said member being provided with a duct, a striker slidably mounted on the frame for movement over said member and toward the tool mounting and provided with a side wall extending at an angle to its direction of travel in position for impingement of fluid from said duct, means for controlling supply of pressure fluid to the 120 125 130

- duct and means for retracting the striker.
14. In a device of the class described, the combination of a frame affording a mounting for a tool, a striker mounted for reciprocation on said frame toward and from the tool mounting, said striker having a cavity with converging lateral walls, a reaction member mounted on the frame in position to be received into said cavity, means for injecting fluid into the cavity between the reaction member and said lateral walls of the striker, and means for moving the striker to receive the reaction member.
15. In a device of the class described, the combination of a frame affording a tool mounting, a striker mounted on said frame for reciprocatory movement, said striker being provided with a longitudinally extending cavity open at its rearward end, a reaction member mounted on the frame for reception into said cavity, said reaction member having an oblique lateral wall portion, means for injecting pressure fluid between said oblique wall portion and the lateral wall of the cavity, and means for effecting movement of the striker onto the reaction member.
16. In a device of the class described, the combination of a frame, a tool mounted thereon, a reaction member and a striker arranged for relative telescopic movement on the frame to provide a pressure chamber between them, the striker being movable off of the reaction member to strike the tool, the reaction member affording a conduit for injection of fluid into the pressure chamber, the striker having parts effective during its movement to vent and close the compression chamber to atmosphere, and means for controlling supply of pressure fluid to the pressure chamber.
17. In a device of the class described, the combination of a frame, a reaction member and striker mounted thereon for relative telescopic movement, a tool movably mounted on the frame in position to be struck by the striker, means being provided for effecting movement of the striker from the tool, said reaction member and striker having cooperating faces arranged to form a pressure chamber, a channel being provided for introduction of pressure fluid into said chamber, and the opposed walls of the chamber diverging from said duct.
18. In a device of the class described, the combination of a frame, a reaction member and striker mounted thereon for relative telescopic movement, means being provided for effecting movement of the striker onto the reaction member, a tool supported on the frame in position to be struck by the striker, said reaction member and striker having cooperating walls disposed to form a pressure chamber, a duct being provided for introduction of pressure fluid into said chamber, and opposed walls of said chamber first diverging and then converging from the duct toward the tool.
19. In a device of the class described, the combination of a frame, a tool mounted thereon, a striker movable on the frame into contact with the tool, a reaction member mounted on the frame for cooperation with the striker to form a pressure chamber, the striker being arranged to telescope the reaction member and having a wall portion diverging from the adjacent wall thereof and a duct being provided for injection of pressure fluid into the pressure chamber between the divergent walls of the striker and reaction member, and means for effecting movement of the striker toward the reaction member.
20. In a device of the class described, the combination with a tool of a striker movable into engagement therewith, said striker having a bore extending longitudinally therethrough a reaction member cooperating with the striker, and a guide member upon which the striker is supported, said guide member and reaction member disposed to close the opposite ends of the bore of the striker to form a pressure chamber, a duct being provided for introduction of pressure fluid into such chamber.
21. In a device of the class described, the combination with a tool, of a striker movable into contact therewith, said striker being provided with an internal cavity, a guide upon which the striker rides forming a closure for said cavity at one end, a reaction member cooperating with the striker to form a closure for said cavity at the other end, a duct being provided for introduction of pressure fluid into the cavity and means operable to effect return of the striker.
22. In a device of the class described, the combination with a tool of a striker movable into engagement therewith, a member disposed axially of said striker and cooperating therewith to form a pressure chamber, means being provided to effect movement of the striker onto said member, a duct being provided for introduction of pressure fluid into said chamber, said striker and axial member having diverging wall portions adjacent the conduit opening and converging wall portions between the latter and the tool.
23. In a device of the class described, the combination of a reaction member, a tool, a striker mounted for reciprocatory movement relative to them and adapted to strike the tool, said reaction member and striker having portions cooperating to afford a pressure chamber, and including means forming an expansion nozzle arranged to direct pressure fluid into said chamber.
24. In a device of the class described, the combination with a tool of a reaction member, a striker member movable relative there-

to, one of said members being provided with a cavity arranged to receive the other thereof, said cavity having a lateral wall converging toward the tool, and means for injecting pressure fluid between said converging wall and a lateral wall of the other member.

In witness whereof, I have hereunto signed my name in the presence of two subscribing witnesses.
